DESIGN FOR A NURSING UNIT

Alvin H. Ostrin and Leon Borstein,
Charleston, W. Va.

Application June 7, 1944, Serial No. 113,895

Term of patent 14 years

(Cl. D83—8)

To all whom it may concern:

Be it known that we, Alvin H. Ostrin and Leon Borstein, both citizens of the United States, residing at Charleston, in the county of Kanawha and State of West Virginia, have invented a new, original, and ornamental Design for a Nursing Unit, of which the following is a specification, reference being had to the accompanying drawing, forming a part thereof.

Figure 1 is a side elevational view of a nursing unit showing my new design, the opposite side of said unit from that shown in Figure 1 is plain;

Figure 2 is a side elevational view of the bottle shown in Figure 1; and

Figure 3 is a side elevational view of the nipple adapter shown in Figure 1.

We claim:

The ornamental design for a nursing unit, as shown and described.
